Attorney

UNITED STATES PATENT OFFICE.

OSCAR C. WHITTEN, OF STAR CITY, ARKANSAS.

SEAT-BOARD FOR VEHICLES.

1,216,755.

Specification of Letters Patent. Patented Feb. 20, 1917.

Application filed February 5, 1916. Serial No. 76,408.

To all whom it may concern:

Be it known that I, OSCAR C. WHITTEN, a citizen of the United States, residing at Star City, in the county of Lincoln and State of Arkansas, have invented certain new and useful Improvements in Seat-Boards for Vehicles, of which the following is a specification, reference being had to the accompanying drawings.

10 This invention relates to an improved seat board for wagons and other vehicles, and has for its primary object to provide adjustable means for yieldingly supporting the seat board in spaced relation to the base 15 upon which it is mounted.

The invention has for another and more particular object to provide a seat board hinged at one of its ends upon a suitable base, and a convoluted leaf spring having a 20 bolt fixed in one end longitudinally adjustable in the base and engaged at its other end with the bottom face of the seat board, the adjustment of said spring toward or from the hinged end of the board varying the normal 25 inclination of the board.

It is a further general object to improve and simplify the construction of devices of the above character, whereby the same may be readily applied in practical use and which 30 consists of comparatively few elements of simple form so that the device will not get out of order.

With the above and other objects in view, my invention consists in the novel features 35 of construction, combination and arrangement of parts to be hereinafter more fully described, claimed and illustrated in the accompanying drawing, in which,

40 Figure 1 is a side elevation of a wagon seat board constructed in accordance with the preferred embodiment of the invention;

Fig. 2 is a section taken on the line 2—2 of Fig. 1; and

45 Fig. 3 is a section taken on the line 3—3 of Fig. 1.

Referring in detail to the drawing, 5 indicates a baseboard which is provided at each end and upon its opposite faces with the bars or cleats 6. Grooves or channels 7 are 50 cut in the opposite ends of the board and said cleats to receive the guide strips 8 on the side walls of the wagon box.

55 The seat board indicated at 9, is hinged at one of its ends, as at 10, to one of the cleats 6 on the base-board 5. Adjacent to this hinged end of the seat board, the base

5 is provided with a longitudinally extending slot 11.

12 designates the convoluted leaf spring which is interposed between the seat board 60 and baseboard 5 and extends transversely thereof. A bolt 13 extends through one end of this leaf spring and through the slot 11 and has a nut 14 threaded upon its lower end for clamping engagement with the bottom face of the board 5. Thus, it will be apparent that the spring may be adjusted longitudinally between the board 5 and the seat board 9. The free end of the spring 12 65 yieldingly supports the seat board in a longitudinally inclined position and, as the spring is adjusted toward the hinged end of the seat board, the inclination of the board will be increased, and when said spring is adjusted inwardly upon the baseboard, the seat board 70 will be lowered with respect to the baseboard. In this manner, it will be seen that the spring board may be permitted to yield vertically to any desired extent.

75 From the foregoing description, taken in connection with the accompanying drawing, the construction, manner of operation and several advantages of the invention will be clearly and fully understood. The mounting and arrangement of the board 9 provides 80 a yielding seat or support for the driver so that he will suffer no great discomfort when the wheels of the wagon encounter obstacles, or enter ruts or depressions in the road surface.

85 It is obvious that if desired, two of the seat boards 9 may be provided and hingedly mounted upon the relatively opposite ends of the baseboard 5 and a pair of the cushioning springs also adjustably arranged between said seat boards and the base 5 adjacent to the opposite ends of the latter. It 90 will be understood, of course, that this arrangement of two independently supported seat boards is employed for the use of two 95 persons, each of which will occupy one of the boards. The device as a whole is very serviceable and convenient in practical use and, in view of the fact that but very few parts are employed, it is apparent that the device will be very durable in practical use and not liable to get out of order. The invention may also be manufactured at comparatively small cost and readily applied to 100 the ordinary vehicle body.

105 While I have shown and described the preferred construction and arrangement of

the several parts, it is to be understood that the device is susceptible of considerable modification therein and I, therefore, reserve the privilege of adopting all such legitimate changes as may be fairly embodied within the spirit and scope of the invention as claimed.

Having thus fully described my invention, what I desire to claim and secure by Letters Patent is:—

1. A seat for vehicles including a base, a seat board proper hinged at one of its ends upon said base, and a leaf spring interposed between the seat board and the base and longitudinally adjustable with respect thereto.

2. A seat for vehicles including a base, a seat board proper hingedly mounted at one of its ends upon said base, a transversely disposed convoluted leaf spring interposed

between the seat board and said base, and means for adjusting said leaf spring longitudinally upon the base.

3. A seat for vehicles including a base, a seat board proper hingedly mounted upon the base at one of its ends, said base being provided with a longitudinal slot adjacent to the hinged end of the seat board, a transversely disposed convoluted leaf spring arranged between the seat board and the base, and a bolt extending through one end of said leaf spring and longitudinally adjustable in said slot.

In testimony whereof I hereunto affix my signature in the presence of two witnesses.

OSCAR C. WHITTEN.
